UNITED STATES PATENT OFFICE.

GEORGE P. FULLER, OF MINNEAPOLIS, MINNESOTA, ASSIGNOR OF ONE-HALF TO ANDREW A. KELLY, OF SAME PLACE.

NUT-LOCK.

SPECIFICATION forming part of Letters Patent No. 338,729, dated March 30, 1886.

Application filed May 19, 1885. Serial No. 166,007. (No model.)

To all whom it may concern:

Be it known that I, GEORGE P. FULLER, a citizen of the United States, residing at Minneapolis, in the county of Hennepin and State 5 of Minnesota, have invented a new and useful Improvement in Nut-Locks, of which the following is a specification, reference being had to the accompanying drawings.

This invention relates to nut-locks; and 10 it has for its object to provide a device of this character which will have a double locking action, so as to hold the nut firmly in its place and prevent it from turning.

With this end in view this said invention 15 consists in the peculiar construction and combination of devices that will be hereinafter more fully set forth, and particularly pointed out in the claims.

In the accompanying drawings, Figure 1 is 20 a perspective view illustrating one of the modes of application of my improved nut-lock. Fig. 2 is a vertical transverse section of the same. Fig. 3 is a detail view of the inner serrated washer. Fig. 4 is a detail view 25 of the outer washer-plate, having slotted points to turn up against the side of the nut. Fig. 5 is a detail sectional view illustrating the peculiar manner of fitting the two washers together, so as to hold them from moving independently of each other.

Like letters are used to indicate corresponding parts in the several figures.

Referring to the drawings, it will be seen that I have shown the lock in its application 35 to rail-joints, in which A is the bolt, B the rail, C the fish-plate, and D the nut.

E designates a circular washer, having a central opening for the passage of the bolt, and provided on its inner face with a series 40 of serrations or raised projections, forming a rasp-surface, as at a, which engages or bears against the fish-plate to hold said washer from turning. On the outer face of the washer, at points diametrically opposite each other 45 around the bolt-hole, are provided rectangular depressions b, for the purpose hereinafter explained.

F designates the outer washer-plate, which is preferably constructed of thin sheet metal, 50 and is provided with a central opening for the passage of a bolt. Around this bolt-hole,

at points diametrically opposite each other, the body of the plate is pressed inward to provide rectangular projections d, which, when the washer is in its normal position, fit 55 within the recess b of the inner washer, E, and thus the outer washer will be held from turning when screwing on the nut. The washer-plate F is circular in form, and is larger in diameter than the nut, the outer periphery or 60 edge of the washer-plate being slotted diagonally, as at e, so as to form points f, any one of which may be bent or turned upward or outward against the side of the nut to lock it from further movement.

The operation of my invention will be readily understood from the foregoing description, taken in connection with the annexed drawings. After the bolt has been passed through the rail and fish-plate the inner washer, E, is 70 passed over the threaded end of the bolt so that its inner serrated face will come in contact with the surface of the fish-plate and take a firm hold against the same. The outer thin washer-plate, F, is then placed over the 75 bolt so that the projections d will register with and be received in the recesses or depressions b of the inner washer. The nut is then turned over the threaded end of the bolt so as to come against the outer washer, F, 80 against which it bears, and holds it in contact with the inner washer, E. By this action of the nut the projection d will be held within the recesses b of the inner washer, and thus both washers will be prevented from moving 85 when turning on the nut, which, when it has reached the limit of its movement, may be held from turning by bending up or out any one of the points f against the side of the nut. It will be understood that where greater security 90 is needed the points f may be bent or turned out to come up against all sides of the nut; but in practice it has been found that one point will serve as an efficient lock for the purpose intended. The inner washer is thicker than the outer washer, and is constructed of steel, and hardened to such a degree that the rasp-surface will take a firm hold upon the part to which the nut-lock is applied.

It will be seen that when applying the nut-locking device the washers are placed on the bolt in such position that when the nut has

been screwed on the points *f* of the outer washer will coincide with the several sides of the nut. Since the inner washer is held by indenture alone against the fish-plate, it will be 5 apparent that a connection between the inner and outer washers is necessary to retain the parts in their proper relative positions. The inner and outer washers cannot be formed in one piece, though in some cases a single washer-plate made of untempered iron or steel with the slotted points *f* around its edge, and provided with a rasp-surface on the side opposite the nut, may be used where it is not necessary to employ a strong lock. Ordinarily I use 10 the nut-lock herein shown and described. The thick inner washer with the rasp-surface will readily withstand the strain that is placed upon it. As the rasp-face binds by indenture alone, there will be no necessity of providing 15 slots or holes (which oftentimes become clogged) in the fish-plate, and besides the rasp-face forms a more efficient lock, as it binds at all parts thereof. It can be slipped over the bolt without the necessity of making any previous adjustment. I therefore lay special 20 claim on the rasp-surface of the inner washer. The reason why the two washers are formed separately is that were they formed in one solid piece sufficiently thick to withstand the strain the points could not be bent up against 25 the side of the nut. Were they made thin to allow bending, then a very weak lock would be provided, and such as would be of little service on railroads or other heavy structures. 30 The solid iron tempered inner washer with the rasp-face could not be combined with the untempered thin outer washer. They must be made separate; but, as it is desired to hold them from moving, the connection shown and 35 described is employed to effect this end. 40 It will be understood that by combining the two washers, as shown and described, an efficient and serviceable lock for nuts is provided, inasmuch as the inner washer will bind firmly 45 against the part to which the lock is applied, while the outer washer will serve to check the nut, and also will be held from moving independently of the inner washer.

I do not wish to limit myself to any particular application of my improved lock, for it is 50

apparent that it may be applied to all machinery where it is desired to hold nuts from turning—as, for instance, on reapers, cars, bridges, and other wood surfaces.

Having described my invention, I claim— 55

1. The herein-described nut-locking device, comprising the inner serrated washer having a series of depressions or recesses and the outer washer-plate having a corresponding number of projections to enter the recesses of 60 the inner washer, the edge of the outer washer being provided with points which may be turned up against the side of the nut, as set forth.

2. The bolt, in combination with the inner 65 washer having a serrated or rasp inner face to bind by indentation alone against the part to which it is applied, a series of depressions or recesses formed in the outer face of the inner washer, and the outer washer-plate provided 70 with a corresponding number of projections to enter the recesses and having a number of points on its edge to be turned up against the side of the nut, as set forth.

3. The herein-described nut-locking device, 75 comprising the inner thick washer having sharp-pointed projections extending from its entire inner face forming a rasp-surface, the several pointed projections each binding by indenture alone against the part to which the 80 lock is applied, so as to avoid the necessity of providing holes or openings for the reception of the projections, and the outer thin plate or washer larger than the inner washer and provided with a series of points any one of which 85 may be turned out against the side of the nut, and means, substantially as described, for holding the outer washer from turning independently of the inner washer after they have 90 been adjusted in position, and yet allowing the said washers to move independently while the adjustment is being effected, as set forth.

In testimony that I claim the foregoing as my own I have hereto affixed my signature in presence of two witnesses.

GEORGE P. FULLER.
